UNITED STATES PATENT OFFICE.

JOHN H. GAULT, OF PHILADELPHIA, PENNSYLVANIA.

DESIGN FOR A POT FOR TABLE USE.

No. 37,545.

Specification for Design.

Patented Sept. 12, 1905.

Application filed June 7, 1905. Serial No. 264,198. Term of patent 14 years.

To all whom it may concern:

Be it known that I, JOHN H. GAULT, a citizen of the United States, residing at Philadelphia, county of Philadelphia, and State of Pennsylvania, have invented a new, original, and ornamental Design for a Pot for Table Use, reference being had to the accompanying drawing for an illustration of the same.

The drawing represents a perspective view of a pot for table use embodying my design.

What I claim is—

The ornamental design for a pot for table use, as shown.

JOHN H. GAULT.
